ENGINE CYLINDER BLOCK AND HEAD GASKET SURFACE GRINDING APPARATUS

Alfred F. Beauloye, Henry Beauloye, Jr., and Max Beauloye, San Diego, Calif.

Application May 18, 1954, Serial No. 430,612

4 Claims. (Cl. 51—56)

Our invention relates to an engine cylinder block and head gasket surface grinding apparatus, more particularly for resurfacing the gasket contacting surfaces of the engine cylinder block and cylinder head and used for the purpose of straightening the warped surfaces of cylinder blocks and cylinder heads in gas engines, and the objects of our invention are:

The main object of this present invention is to provide improvements over our cylinder block resurfacing machine disclosed in our application for patent which was filed in the United States Patent Office May 11, 1953, under Serial No. 354,049, now abandoned, and the objects of our improvements are:

First, to provide an apparatus for quickly and accurately resurfacing the gasket engaging surfaces of an engine cylinder block or head.

Second, to provide a new and novel apparatus for supporting and properly positioning the V-type engine cylinder block and head for resurfacing both the block and head.

Third, to provide a novel apparatus for positioning the cylinder block in accurate relation in the path of a surface grinding wheel.

Fourth, to provide an accurate positioning and securing apparatus that both provides a surface for grinding uniformly and for depth grinding.

Fifth, to provide an apparatus of this class that provides for a quick and easy positioning and securing of an engine cylinder block and head.

Sixth, to provide an apparatus of this class in which the engine cylinder block is supported by a bar engaging the engine block shaft bearings, thus providing accuracy of the cylinder head with respect to the crank shaft of the engine.

Seventh, to provide an apparatus of this class that utilizes a large number of the same parts for the cylinder block and the head as positioning and securing apparatus.

Eighth, to provide an apparatus for grinding that provides for cooling the grinding apparatus and grinder and also for washing the grindings out of the way, thus providing for deep grinding without surface burning or overheating, and

Ninth, to provide an apparatus of this class which is very simple and economical of construction in accordance with the results obtained, easy to operate, easy to install the cylinder block and head for resurfacing, very efficient in its action, and which will not readily deteriorate or get out of order.

With these and other objects in view as will appear hereinafter, our invention consists of certain novel features of construction, combination and arrangement of parts and portions as will be hereinafter described in detail and particularly set forth in the appended claims, reference being had to the accompanying drawings, and to the characters of reference thereon, which form a part of this application, in which:

Figure 1 is a fragmentary end elevational view of our

improved apparatus showing it in operative relation with a straight engine cylinder block shown in dash line. Fig. 2 is a fragmentary sectional view taken from the line 2—2 of Fig. 1. Fig. 3 is an enlarged fragmentary sectional view taken from the line 3—3 of Fig. 2 and showing a portion broken away and in section to facilitate the illustration. Fig. 4 is a fragmentary enlarged sectional view taken on the line 4—4 of Fig. 2. Fig. 5 is a fragmentary sectional view taken from the line 5—5 of Fig. 1. Fig. 6 is an enlarged sectional view taken from the line 6—6 of Fig. 5 and showing a portion broken away and in section to facilitate the illustration. Fig. 7 is a fragmentary end elevational view showing some of the parts as in Fig. 1 and showing the apparatus for positioning the engine cylinder head shown by dash lines. Fig. 8 is a similar view as that of Fig. 7 shown at a right angle thereto. Fig. 9 is a fragmentary end view of some of the parts shown in Fig. 1 and showing our improved apparatus for accurate adjustment alinement of a V-type engine cylinder block for grinding one of the gasket-engaging surfaces and showing the block in dash line. Fig. 10 is an elevational view of the improved grinding portion of our apparatus showing the improved cooling and grinding washing apparatus, and Fig. 11 is an enlarged fragmentary sectional view taken from the line 11—11 of Fig. 10, but showing a fragmentary portion in elevation to facilitate the illustration.

Similar characters of reference refer to similar parts and portions throughout the several views of the drawings.

30 The side plates 1 and 2, bed plate 3, engine block bar support 4, engine block support bar 5, engine block securing bar 6, engine block securing bar bolts 7, 8 and 9, grinding wheel 10, grinding wheel support 11, grinding wheel drive shaft 12, grinding wheel supporting bracket 13, engine block level indicator lever 14, engine block level indicator base 15, engine block level indicator supporting bar 16, engine block level indicator supporting bar bracket 17, chain 18, sprocket 19, wheel 20, micrometer hand wheel 21, casing 22, engine head supporting base 23, head supporting bolts 24, head leveling upright 25, head leveling horizontal 26, V-8 engine block leveling bolt 27, V-8 engine block leveling bracket 28, water baffle member 29, and water supply pipe 30, constitute the principal parts and portions of our engine cylinder block and head gasket surface grinding apparatus.

It will be here noted that the apparatus for reciprocating the grinding wheel and maintaining the grinding wheel in its proper relation with the bed plate is substantially the same as that disclosed and described in our former application for patent for Cylinder Block Resurfacing Machine filed May 11, 1953, Serial No. 354,049, now abandoned, and therefore no part of our present invention, and therefore only a portion is shown in the present application.

55 The side plates 1 and 2 and sprocket wheel, chain and hand wheel, designated 18, 19 and 20, are shown fragmentarily to disclose their relation with the rest of the apparatus. The side plates 1 and 2 are provided with sets of rollers 1a which engage a rib 1b on the base to permit reciprocation of the grinding wheel frame 13.

The bed plate 3 is provided with a straight, level upper horizontal surface throughout its whole area and is of sufficient width and length to accommodate the longest and widest engine cylinder blocks. Secured midway between the side edges of this bed plate are a plurality of engine block bar supports 4, which are provided with extended base portions 4a in which are mounted bolts 4b for securing said supports 4 rigidly to the bed plate 3. These blocks 4 are provided at their upper ends with notches 4c which are adapted to receive the lower portion of the engine block supporting bar 5, all as shown best in

Figures 1 and 9 of the drawing. This supporting bar 5 is beveled at its opposite sides at its upper edge leaving a narrow flat portion 5a to provide a narrow engaging portion of this bar 5 for engagement with the engine cylinder block bearings shown by dash line in Figures 1 and 9 of the drawings. This supporting bar 5 is provided in its upper edge near one end with a notch 5b which extends some distance from the upper edge thereof and positioned centrally in this notch and extending through the remainder of the member 5, is a threaded hole 5c in which is screw-threaded a bolt 5d. This bolt 5d is provided with a head that is frusto-conical in shape. This bolt is provided for the engagement and support of engine cylinder block bearings, some of which are out of alignment with the remainder of the shaft bearings and are adjustable in the hole 5c for their proper relation for the support of such bearings, all of which is shown best in Fig. 6 of the drawing. Thus it will be noted that the engine cylinder block is pivotally mounted on this bar 5. The straight-type of engine block, as shown by dash line in Fig. 1 of the drawings, is leveled so that it is in accurate horizontal position at its top side by means of a level indicator which includes a base 15 which is positioned on the upper side of the block as shown best in Figs. 1 and 2 of the drawings. Pivotally connected to one side of this base member 15 is a level indicator supporting bar 16 by means of a horizontal bar 16a, and this supporting bar 16 extends upwardly a considerable distance and is supported intermediate its ends by the supporting bar bracket 17 which is secured to the grinding wheel supporting bar bracket 13 by means of bolts 17a. This bracket 17 is provided with an enlarged portion surrounding the supporting bar 16 and is provided with a slotted portion 17b, thus providing a clamp portion for clamping it in certain positions on the supporting bar 16 by means of a clamp screw 17c, shown best in Figures 2 and 4 of the drawings. And this bar 16 is further secured in various positions on the bracket 17 by means of a lock washer 17d. On the upper end of the bar 16 is provided an angular index member 16b. Secured to the indicator base 15 intermediate its ends is an extended hub portion 14a in which is secured the engine block level indicator lever 14 which extends upwardly at an accurate right angle to the indicator base 15, so that when the indicator lever 14 is in alignment with the upper extended end of the level indicator 16b the upper end of the cylinder block is on a horizontal level supported on the engine block supporting bar 5, and it is adjusted and secured in this level position by means of the bolt 7a which is provided with a screw-threaded portion which is screw-threaded in the supporting portion 7 resting on the bed plate 3 and this bolt 7a is provided with a nut-like portion to facilitate its turning for adjustment of the cylinder block in a level position at its upper side. This bolt 7a is also provided with a reduced portion 7b which is arranged to fit into one of the crank case bolt holes in the cylinder block, as shown best in Fig. 1 of the drawings. The cylinder block is further secured by means of the engine block securing bar 6, the one end of which is arranged to rest on the flange portion of the cylinder block and its other end is provided with a hub portion 6a which is secured to the bolt 9 by means of a set screw. This securing bar 6 is preferably made of spring steel so that it will yield slightly intermediate its ends when the nut 8a on the bolt 8 is turned tightly against the bar 6, thus providing a spring-like tension against the upper side of the flange portion of the cylinder block. The bolt 8 is provided with a base portion 8b which is secured to the bed plate 3 by means of a bolt 8c which is positioned in a slot 8d providing a longitudinal adjustment of the member 8b which provides for varying length engine cylinder blocks. It will be here noted that there are a plurality of these groups of engine block securing bolts 7a, 8 and 9, and their related parts, so that there

may be 2 or more securing points along one side of the engine block. The bar 16d which is carried by the lower end of the supporting bar 16 is provided at its opposite ends with brackets 16c which extend over the base 15 and are adapted to hold the base 15 substantially in alignment with the bar 16d, all as shown best in Figs. 2 and 3 of the drawings.

In Fig. 9 is shown the apparatus for supporting the V-8 type of cylinder block in level position in which the bed plate 3 is the same as is shown in the other views of the drawings and the engine block bar support 4 and engine block supporting bar 5 are the same as that shown in the other views of the drawing. However, the block is leveled by the apparatus shown in Figs. 1, 2 and 3 of the drawings for leveling the straight cylinder block, and it is supported in this leveled position by means of L-shaped brackets 28 which are secured to the engine block by bolts 28a. The other arm of the bracket 28 is provided with a hub portion 26 having a screw-threaded hole in which is screw-threaded the bolt 27, while the end of the bolt 27 is provided with a ball-bearing 27b positioned centrally in the end of the bolt with the ball bearing engaging the upper surface of the bed plate 3, and this bolt is turned by means of a head 27c which is extended for leverage purpose. It will be here noted that the V-type cylinder block may be tilted on the bar 5 so that the other portion of the cylinder block assumes a horizontal position and the one now in horizontal position is in a vertical position and the brackets 28 and bolts 27 may be used on the vertical side in the same manner, it being noted that the cylinder head is so much out of balance that its weight holds it in secure position with the ball bearing portion 27 resting on the upper surface of the bed plate 3.

In Figs. 7 and 8 are shown the apparatus for supporting a cylinder head in proper level position for grinding the cylinder head by the same reciprocating grinder apparatus as that disclosed in our former application for Cylinder Block Resurfacing Machine, filed May 11, 1953, Serial No. 354,049, in which case the same bed plate 3, bolts 7, 8 and 9, cylinder block bar support 4, engine block supporting bar 5, engine block securing bar 6, and grinding wheel 10 and its operating parts, are used. However, there is provided a head supporting base 23 which is longitudinally slotted at its lower side at 23a arranged to fit upon the bar 5 in snug relation therewith. This bar is adjusted and this base 23 is adjusted and supported by means of the bolts 7, 8 and 9, and bar 6 in engagement with the lower side of the recess 23d in the one side of this base member 23 and has the same action relative to this base member as it had to the engine block as shown in Fig. 1 of the drawings. This base member 23 is also provided with a pair of box-like portions 23b in each of which is vertically reciprocal the head leveling upright member 25 which is provided with a plurality of notches 25a arranged to be engaged by the end of a set screw 23c which is screw-threaded into the member 23b, it being noted that there are two of these members 25 one in each end of the base member 23 and extending upwardly adjacent the opposite ends of the cylinder head shown by dash lines in Figs. 7 and 8. Secured to the upper ends of the member 25 at right angles thereto are the head leveling horizontal members 26 which extend transversely over the head of the engine cylinder head gasket engaging surface, facing upwardly, and the cylinder head is supported by means of adjusting bolts positioned in the members 24 of which there are four or more positioned at opposite corners of the cylinder head in the head supporting bolt holes, thus providing for the accurate leveling of the cylinder head relatively to the bed plate 3, and therefore relative to the grinding wheel for grinding the gasket engaging surface of the cylinder head. This cylinder head is further secured by use of bolts 23e which bolts are mounted in the spark plug holes in the

cylinder head at their upper ends and in the upper portion of the member 23 at their lower ends.

In Figs. 10 and 11 is shown a grinding apparatus as shown in Fig. 1 of the drawings but which includes the motor in connection with its support in relation with the grinding wheel, but provision is made for cooling and cleaning the grinding surface of the grinding wheel as well as the motor shaft and operating parts intermediate the motor and the grinding wheel by forcing water through the shaft 12 which is the grinding wheel drive shaft which extends from the grinding wheel to the opposite end of the motor which shaft is hollow and water is introduced into the upper end through water pipe 12a which has one end communicating with the upper end of the hollow drive shaft 12 and connects with a water service pipe. The water is forced down through this shaft, through the motor, and down to the grinding wheel 10 where it strikes a baffle member 29, which is a circular baffle member which forces the water from the shaft 12 outwardly between the periphery of said baffle member 29 and the inner wall of the grinding wheel 10, then under the lower surface of the grinding wheel forcing the grindings from the wheel outwardly away from the grinding wheel, all as shown by arrows in Fig. 11 of the drawings.

It will be here noted that applicants have shown and described a particular apparatus that is applicable for accurately grinding the gasket surface of straight engine cylinder blocks and V-type cylinder blocks, and also for grinding the gasket surface of engine cylinder heads, and for accurately leveling said cylinder blocks and cylinder heads, to properly and accurately position the work and this apparatus has provided means for cooling the grinding wheel as well as at the same time washing the grindings from around the grinding wheel, thus preventing overheating and surface burning the gasket surface of the engine cylinder block and cylinder head.

The operation of our engine cylinder block and head gasket surface grinding apparatus is substantially as follows: The engine cylinder block is placed in position with the bearings positioned on the bar 5 with the gasket engaging surface positioned substantially horizontal as shown by dash lines in Figs. 1 and 9 of the drawings, and the carriage with the side plates 1 and 2, and grinding wheel supporting bracket 13 are shifted to a suitable position over the engine cylinder block and the level indicator base 15 lowered onto the upper surface of the block by lowering the level indicator supporting bar 16. The bolt 7a is then revolved by means of the nut-like portion thereon until the level indicator lever 14 is in alignment with the indicator member 16b. Then the nut 8a is tightened onto the engine block securing bar 6 thus securing the engine block in an accurately level position for the grinding wheel. It being noted that there are two or more of these groups of bolts 7a, 8 and 9 along one side of the engine cylinder block on the bed plate 3. However, with the V-type block which is leveled in the same manner, it is supported by means of the bolt 27 of which there may be several on the one side and when the other gasket engaging surface is to be ground the engine cylinder block is shifted so that the other face of the block is in nearly horizontal position as hereinbefore described. After the block is leveled the level indicator may be raised to a position out of the way for the operation of the grinding wheel and secured in this raised portion by the clamping bolt 17c, thus holding it in any position desired in relation to the supporting bracket 13. The grinding wheel is then lowered by means of the micrometer hand wheel 21 to a position for accurate grinding of the gasket surface of the engine cylinder block, be it either the straight type or the V-type cylinder block. When grinding the cylinder head it may be leveled and supported in the same manner by use of the bolts 7a, 8 and 9 with the securing bar 6 in engagement with the lower side of the recess 23d in the head support-

ing base 23; however in Figs. 7 and 8 applicants have provided a pair of square members consisting of members 25 and 26 which are raised and lowered near the opposite ends of the gasket surface of the cylinder head and it is secured in the same manner by means of the bolts 7a, 8 and 9, after which the square members 25 and 26 are removed and the cylinder block is held by means of the bolts in members 24 which are extended into the securing holes of the cylinder head at the four corners, and the grinding wheel operated as hereinbefore described for the cylinder block.

Though we have shown and described a particular construction, combination and arrangement of parts and portions, we do not wish to be limited to this particular construction, combination and arrangement, but desire to include in the scope of our invention the construction, combination and arrangement substantially as set forth in the appended claims.

Having thus described our invention, what we claim as new and desire to secure by Letters Patent, is:

1. In an engine cylinder block gasket surface grinding apparatus, the combination of a large bed plate provided with an accurate and level upper surface, a bar extending centrally of said bed plate and positioned with its upper surface in accurate alignment with the upper surface of said bed plate, said bar being arranged to engage and rockably support said cylinder block at a point below its center of gravity, securing means arranged along one side of said bar for positioning and securing said engine block with its upper surface in true horizontal alignment with the upper surface of said bed plate, leveling means for indicating the true and accurate alignment of said engine block, and a reciprocating grinding wheel mounted above said bed plate and supporting means for holding said grinding wheel in accurate alignment with the upper surface of said bed plate.
2. In an engine cylinder block gasket surface grinding apparatus, the combination of a large bed plate provided with an accurate and level upper surface, a bar supported on said bed plate and extending centrally thereof with its upper surface in accurate alignment with the upper surface of said bed plate, said bar being arranged to engage and rockably support said cylinder block at a point below its center of gravity, means for securing said cylinder block in an adjusted position with respect to the upper surface of said bed plate, indicating means to indicate the level position of said cylinder block with its upper surface in accurate alignment with the upper surface of said bed plate, a grinding wheel mounted above said bed plate with its radial face arranged to be presented to the gasket surface of said cylinder block, supporting means for holding said grinding wheel in accurate alignment with the upper surface of said bed plate and supports along at least one side of said bar on the upper surface of said bed plate for supporting said engine cylinder block.
3. In an engine cylinder block gasket surface grinding apparatus, the combination of a large bed plate provided with an accurate level upper surface, a bar supported on said bed plate and extending centrally thereof with its upper surface in accurate alignment with the upper surface of said bed plate, said bar being arranged and adapted to rockably support said cylinder block at a point below its center of gravity, leveling and securing means for positioning and securing the engine block with its upper surface in accurate alignment with the upper surface of said bed plate, a grinding wheel reciprocably supported above said bed plate, means for holding said grinding wheel in accurate alignment with said bed plate, supports on the upper surface of said bed plate in spaced relation one from the other to hold said cylinder block in an adjusted position, a level indicator associated with said engine block, said level indicator including a square having a straight edge adapted to engage the cylinder

block to indicate its correct position with respect to the upper surface of said bed plate.

4. In an engine cylinder block gasket surface grinding apparatus, the combination of a bed plate provided with an accurate level horizontal surface, a supporting bar extending centrally of said bed plate positioned in alignment with the upper surface thereof and adapted to engage the bearing surfaces of an engine block to rockably support said block, a grinding wheel reciprocably mounted above said bed plate with its radial wall in true horizontal alignment with the surface of said bed plate, means adjustably engaging said cylinder block along at least one side of said bar for supporting said engine block with its gasket surface in true alignment with the surface of said bed plate and a level indicator associated with said apparatus to indicate the true position of said gasket surface with respect to the surface of said bed plate, said level indicator being arranged to be shifted and adjusted upwardly and downwardly above said engine block whereby said engine block gasket surface can be

accurately presented to the grinding wheel during its to and fro movement thereabove.
